ELECTROACOUSTICAL APPARATUS

Leslie J. Anderson, Westmont, N. J., assignor to
Radio Corporation of America, a corporation
of Delaware

Application March 31, 1936, Serial No. 71,849

3 Claims. (Cl. 175—21)

This invention relates to electroacoustical apparatus, such as microphones, pick-up devices, and the like, and more particularly to the means in such apparatus for maintaining the magnet structure and pole piece structure in clamped relation.

It has been customary, in devices of this sort, to tap the ends of the magnets and secure the pole pieces thereto by means of screws, for example. Considerable difficulty has, however, been experienced in holding the magnets in place, particularly in various types of velocity microphones, for the reason that the magnets are formed of very hard steel which is difficult to drill and tap. The problem is additionally difficult because the clamp must be so designed that it will not disturb the acoustic performance of the microphone.

The primary object of my invention is to provide improved clamping means for clamping together the magnet and pole piece structures, which clamping means will be free from the disadvantages of prior art clamping devices.

More specifically, it is an object of my invention to provide improved clamping means, as aforesaid, which will not only maintain the magnet and pole piece structures in properly cooperable relation, but which will not disturb the acoustic performance of microphones in which the clamping structure is embodied.

A further object of my invention is to provide an improved clamping device of the type described which will be adjustable to clamp the pole pieces to the magnet with a variable clamping force.

Still a further object of my invention is to provide improved clamping structure, as aforesaid, by means of which the danger of disturbing the relation between the pole pieces and the magnet by reason of mechanical shock will be practically entirely eliminated.

Another object of my invention is to provide improved clamping structure of the type set forth which will permit conservation of space and structure.

It is another object of my invention to provide improved clamping means of the type aforesaid which is very simple in construction, which is economical of manufacture, which may be quickly and easily applied in place during assembly, and which is highly efficient in operation.

In accordance with my invention, I provide a thin, resilient strip which is arranged to embrace the magnet and is adjustably secured to the pole pieces resting on the ends of the magnet in a manner such that the resilient strip may be drawn tightly against the magnet without materially affecting the alignment of the pole pieces with

each other or with the magnet, whereby the pole pieces are drawn into firm engagement with the magnet.

The novel features that I consider characteristic of my invention are set forth with particularity in the appended claims. The invention itself, however, as well as the method of operation thereof, together with additional objects and advantages thereof, will best be understood from the following description of a specific embodiment thereof, when read in connection with the accompanying drawing in which,

Fig. 1 is a front elevation, partially in section, showing my improved clamping means applied to a U-shaped magnet and its associated pole pieces, and

Fig. 2 is a side elevation thereof.

Referring more specifically to the drawing, wherein similar reference characters designate corresponding parts throughout, there is shown a U-shaped magnet 1 on the ends of which rest the pole pieces 3 and 5 having lateral extensions 7 and 9, respectively. Embracing the magnet 1 around its periphery is a thin, resilient strip 11, preferably of brass, the ends of which are bent around the extensions 7 and 9 in spaced relation thereto, as clearly shown in Fig. 1. The ends of the resilient strip 11 may be reinforced by sheet brass plates 13, as by brazing or the like.

Threadedly received within the ends of the strip 11 and the plates 13 are the screws 15 and 17 which bear, respectively, against the lateral extensions 7 and 9, while a plurality of screws 19 and 21 are loosely received in the ends of the strip 11 and the plates 13 and are threaded into the extensions 7 and 9, respectively, of the pole pieces 3 and 5. The pole pieces 3 and 5 are connected to each other in any suitable way, as by a pair of screws 23 which are threaded therein and are received by a block 25 of insulating material between which and a conducting strip 27 is clamped one end of a conductive ribbon 29 mounted for vibratile movement in the air gap between the pole pieces 3 and 5. In operation, as the screws 17 are advanced in the plates 13, they draw the resilient strip 11 tightly against the magnet 1, while at the same time applying a force against the pole piece extensions 7 and 9 in the direction of the arms of the magnet. The screws 19 and 21 may also be adjusted to prevent tilting of the plates 13 with respect to the pole piece extensions 7 and 9 under the influence of the screws 15 and 17. It will therefore be seen that, by means of the differential action between the two sets of screws 15—19, and 17—21, it is

possible to draw the clamp 11 up tightly and evenly without affecting the alignment of the pole pieces and the magnet.

Although I have shown and described but a single embodiment of my invention, I am fully aware that many modifications thereof are possible. For example, in place of the screws 15-19 and 17-21, any suitable means may be provided which will place the clamp 11 under tension upon relative adjustment of said means. Also, in place of a single magnet, a plurality of magnets may be used as, for example, a pair of magnets each associated with corresponding ends of extensions 7 and 9. Many other changes will, no doubt, readily suggest themselves to those skilled in the art. I desire, therefore, that my invention shall not be limited except insofar as is made necessary by the prior art and by the spirit and scope of the appended claims.

20 20 I claim as my invention:

1. In electromagnetic apparatus, a magnet, a plurality of pole pieces associated with said magnet, resilient means embracing said magnet and at least a portion of said pole pieces for maintaining said pole pieces in cooperative relation with said magnet, and relatively adjustable means associated with said resilient means and with each of said pole pieces for placing said resilient means under tension whereby to cause said resilient means to draw said pole pieces firmly against said magnet, said relatively adjustable means being adjustably received by said resilient means and arranged to apply a force on its associated pole piece in a direction toward said magnet.

35 25 30 35 2. In electromagnetic apparatus, a magnet, a

plurality of pole pieces associated with said magnet, resilient means embracing said magnet and at least a portion of said pole pieces for maintaining said pole pieces in cooperative relation with said magnet, and relatively adjustable means associated with said resilient means and with each of said pole pieces for placing said resilient means under tension whereby to cause said resilient means to draw said pole pieces firmly against said magnet, said relatively adjustable means comprising a pair of relatively movable members one of which is adjustably received by said resilient means and is arranged to apply a force on its associated pole piece in a direction toward said magnet, and the other of which is adjustably received in its associated pole piece and is arranged to limit the relative movement between said resilient means and said pole piece.

3. In electromagnetic apparatus, a U-shaped magnet, a pole piece associated with each end of said magnet, means connecting said pole pieces to each other against relative displacement, a resilient strip in engagement with the periphery of said magnet and having its ends bent around a portion of said pole pieces, a screw extending loosely through each end of said strip and threadedly received in its associated pole piece, and a second screw threadedly received in each end of said resilient strip and bearing against its associated pole piece, the differential action between said screws serving to tension said strip whereby to draw said pole pieces into firm engagement with said magnet while maintaining said pole pieces and magnet in aligned relation.
